SOLE PLATE FOR A GOLF CLUB HEAD

Robert J. Mader, Torrance, Calif., assignor to Mader
Products, Inc., Gardena, Calif.

Filed Apr. 18, 1974, Ser. No. 462,021

Term of patent 14 years

Int. Cl. D21—02

U.S. Cl. D34—5 GC

FIG. 1

FIG. 2

FIG. 3

FIG. 5

FIG. 4

FIG. 6

FIG. 7

FIG. 1 is a perspective view of the sole plate showing my new design;

FIG. 2 is a top plan view of the sole plate;

FIG. 3 is a side elevation view of the sole plate;

FIG. 4 is a bottom plan view of the sole plate;

FIG. 5 is a side elevation view of the sole plate from the side opposite to that shown in FIG. 3;

FIG. 6 is a front elevation view of the sole plate; and

FIG. 7 is a rear elevation view of the sole plate.

I claim:

The ornamental design for a sole plate for a golf club head, as shown.
